DIRECTION INDICATOR

Application filed November 4, 1927. Serial No. 231,091.

Our invention relates to improvements in direction indicators for motor vehicles, the objects of which are to provide means simulating the hand signalling in vogue, which is 5 operable from any convenient position on the dash board or steering column of the vehicle.

The invention consists essentially of a pivotally mounted translucent arm adapted for attachment to the side post of a window shield, and in which an electric bulb is fitted, and means for swinging the arm into various positions to indicate the driver's immediate intention as to the movement of his vehicle, as will be more fully described in 15 the following specification, in which:—

Fig. 1 is a general view of the indicator with the switch cover removed and a portion of the lamp cover broken away.

Fig. 2 is a sectional view of the operating mechanism taken on the line 2—2 of Figure 1.

In the drawings like characters of reference indicate corresponding parts in each figure.

25 The numeral 1 indicates generally a plate having apertures 2 adjacent one end for the reception of screws or other fastening means, whereby the device is secured in a suitable position on a motor car. The outer end of 30 the plate is substantially circular in form as at 3 and is fitted with a cover 4 secured by any suitable means. An offset plate 5, see Figure 2, is supported from the plate 1 and in parallel relation thereto, to permit of an 35 indicating arm generally indicated by the numeral 6, being swingingly mounted therebetween.

The indicating arm 6 comprises a boxlike base portion 7 having side plates 8 and pins 40 9 and 10 forming trunnions upon which the arm swings. Secured to the base portion 7 is an elongated casing 11 preferably formed in the shape of a dart and having front and rear openings 12 covered with a suitable 45 translucent material preferably red in colour at the rear and green at the front. Carried between the plates 8 is a socket 13 and an electric bulb 14. In the device as shown the socket 13 is grounded to the base portion 50 7 and through the plate 1 to the metal por-

tions of the vehicle, and a wire 15 is taken from the socket through to an insulated contact 16 projecting concentrically from the pin 10. The pin 10 is provided with a flange 17 at its outer end which serves as an anchorage 18 for one end of a coil spring 19, the opposite end of said spring being bent as at 20 and anchored to the plate 1, the spring being so applied as to draw the indicator arm 6 downward and to hold it against vibration when the vehicle to which it is fitted is in motion.

The plate 1 is provided with an arcuate slot 21 concentric with the pin 10 through which a pin 22 extends and is pivotally secured to the base portion 7 as at 23. The outer end of the pin 22 is slotted as at 24 and is adapted to receive a pull wire 25 having a button 26 at its inner end, which wire is held against lifting from the slot 24 by a split pin 27 extending thereacross. Suitably supported from the base plate 1 is a flexible tube 28 which forms a housing for the pull wire 25 and is attached at its outer end to a suitable controlling device adjacent the 75 driver's seat, whereby as the wire 25 is pulled, the indicating arm 6 is swung upwardly and outwardly to indicate the contemplated action of the driver. Secured to the plate 1 is a block of insulating material 80 29 upon which is mounted a spring contact arm 30 extending over the contact button 16 and adapted to contact therewith. The contact arm is connected within the lighting circuit by a conductor 31. As a means of 85 breaking the contact between the contact arm 30 and the button 16 an insulating stud 32, having a dome shaped upper extremity 33, is provided upon the flange 17 of the pin 10 in such a position as to slide under the arm 90 30 to raise it from contact with the button 16 as the indicating arm 6 is lowered out of indicating position, thus breaking the electric lighting circuit.

It will be obvious that as the control device is operated to pull the wire 25 and swing the indicating arm 6 outwardly and upwardly, that the stud 32 will be withdrawn from under the contact arm 30, thus closing the electrical circuit and illuminating the 100

bulb 14, thereby rendering the device conspicuous to other users of the road.

What we claim as our invention:

A direction indicator comprising a supporting plate, a signal arm secured to the plate by a pivot about which the arm is movable to and from indicating positions, a projecting pin having one terminal rotatably secured to said arm and the other terminal protruding through an arcuate slot formed in said supporting plate, said slot being concentric to said pivot, and means secured to the protruding terminal of said pin to move the pin longitudinally of said slot in order to effect swinging movement of said arm to a direction signalling position.

Dated at Victoria, B. C., this 24th day of Oct. 1927.
